UNITED STATES PATENT OFFICE.

WILLIAM G. STOCKHAM, OF PIQUA, OHIO.

RAILROAD-CROSSING.

1,380,433.

Specification of Letters Patent. Patented June 7, 1921.

Application filed July 3, 1920. Serial No. 393,850.

To all whom it may concern:

Be it known that I, WILLIAM G. STOCKHAM, citizen of the United States, residing at Piqua, in the county of Miami and State of Ohio, have invented certain new and useful Improvements in Railroad-Crossings, of which the following is a specification.

This invention relates to improvements in railroad crossings.

10 An important object of the invention forming the subject matter of this application is to provide a railroad crossing embodying a turn-table provided with rail sections which may be alined with either 15 of the intersecting tracks so that the slots which are ordinarily formed in the rails at the intersecting points of the same may be eliminated.

20 A further object of the invention is to provide a railroad crossing having novel means whereby the turn-table of the same may be readily and conveniently operated with a minimum expenditure of power.

25 A further object of the invention is to provide a railroad crossing having novel means whereby the turn-table is enabled to withstand the strain caused by the passage of the rolling stock over the crossing.

30 The invention forming the subject matter of this application aims also to provide a railroad crossing which is simple, durable and efficient.

35 Other objects and advantages of the invention will be apparent during the course of the following description.

In the accompanying drawings, forming a part of this application and in which like numerals are employed to designate like parts throughout the same:

40 Figure 1 is a plan view of the improved railroad crossing,

Fig. 2 is a side elevation of the same,

Fig. 3 is also a side elevation of the improved railroad crossing, the view being 45 taken at right angles to Fig. 2,

Fig. 4 is a central vertical sectional view through the railroad crossing,

Fig. 5 is a side elevation of a signal embodied in the invention, and

50 Fig. 6 is a rear elevation of the signal.

In the drawings, wherein for the purpose of illustration is shown a preferred embodiment of the invention, the numeral 10 designates a base which may be said to be in 55 the form of a truncated cone and which is

hollow so that a table 11 may be extended into the same. As illustrated in Fig. 4, the table 11 is preferably in the form of a solid steel casting to provide the desired strength and weight and has its lower end terminating in a journal 13. The journal 13 thus formed at the lower portion of the table 11 is rotatably arranged within a boss 15 formed at the lower portion of the base 10 and is lubricated as the occasion requires by 60 a lubricant supplied through a greased passage 16.

The upstanding annular side wall 18 of the base 10 and the outer edge portion of the table 11 are formed in their opposed 70 sides with semi-circular annular grooves which coöperate in forming an annular raceway 20 within which ball bearings 22 or other anti-friction devices may be arranged. The ball bearings 22 arranged in the annular raceway 20 provide a means whereby the table 11 may be rotated with a minimum expenditure of power. As illustrated in Fig. 4 of the drawings, the table 11 has its outer edge portion provided with a downwardly extending annular flange 24 which is seated within an annular rabbet 25 in the adjacent portion of the base 10 so as to provide a dust-proof connection between the table and the base and so as to prevent lateral movement of the table with relation to the base. In providing the dust-proof connection between the table and the base at the outer side of the same, the ball bearings 22 are reliably protected. It is obvious, of 85 course, that the annular raceway 20 will be provided with a packing of grease within which the ball bearings 22 may operate and any suitable means may be employed for periodically supplying a lubricant to the 90 raceway. The rotating table 11 may be mounted upon the base by connecting the table to a derrick or other lifting device through the medium of a loop 28 and gradually lowering the table until the same is 100 seated. The loop 28 is arranged centrally upon the rotating table 11 and is provided with an attaching member 30 embedded in the table and being in the form of a T.

As illustrated in Fig. 1, the table 11 is 105 provided with a pair of spaced parallel rail sections 12 which are confined between upstanding lugs 31 having bolts 32 which also extend through the web portions of the rails. Collars or other suitable spacing elements 110

33 may be arranged between the pairs of lugs and the webs of the rails so as to securely hold the several rail sections in position.

The spaced parallel rails 12 are adapted to be alined with either pairs of rails 34 or pairs of rails 36 which are disposed at right angles to the rails 34 and would, if continued, intersect the rails 34. The pairs of spaced parallel rails 36 are in sections which are disposed at opposite sides of the table so that a train may pass along the track formed by the rails 36 and continue over the table since the rails 12 may be alined with the rail sections 36. The rail sections 36 have their end portions mounted on upstanding brackets 28 having lugs 40 arranged on opposite sides of the rail sections and connected to the rails by means of bolts 42. Suitable spacing elements are disposed between the upstanding lugs 40 and the rails 36 so as to secure the rails against lateral movement.

The rails 34 which are arranged in pairs are mounted upon upstanding brackets 44 formed integral with the base and having pairs of lugs 46 between which the rails are arranged. Bolts 48 are extended through the lugs 46, the webs of the rails, and through spacing elements 50 which form a means for securing the rails in position.

The table 11 may be rotated a quarter of a turn by means of a worm 52 which is engaged with a rack 53 formed in the periphery of the table. As illustrated in Fig. 2, the worm 52 is mounted upon a shaft 54 having connection with a suitable source of power and operated within bearings 55 carried by bearing brackets 56. The latter are formed integral with the base. The rotation of the table is, however, limited by means of a radially directed shoulder 58 carried by the table and adapted to engage the end walls of slots 60 and 61 formed in the base adjacent the corner portions of the same. In this manner, the rails when alined with either of the tracks may be securely held in position or against movement in one direction and the worm holds the table against accidental movement in the other direction. The base 10 is preferably arranged upon a strong foundation of cement or stone so that the vibration caused by the passage of rolling stock over the table will not cause the settling or movement of the same. However, any slight settling of the base will not render the table inoperative since the end portions of the tracks 34 and 36 are secured to the base and may, therefore, be accurately alined with the rail sections 12. The base is provided with a plurality of loops 59 by means of which the base may be suspended from a derrick or the like when it is desired to set the same in position.

In adjusting the table for the passage of a train over the rails 36, the worm, of course,

is rotated for imparting a quarter of a turn to the table 11 whereby the rails 12 of the same may be alined with the rail sections 36. This allows of the free passage of the train over the table onto the rail sections 36 at 70 the opposite side of the base. Attention is invited to the fact that ends of the rails 12 and the adjacent ends of the rail sections 36 and 34 are curved transversely so that the table may freely rotate and so as to provide 75 good joints between the rail sections 12 and the rail sections 34 and 36.

A pair of signal lamps 70 may be mounted upon the table on the outer sides of the rail sections 12 so that approaching engineers 80 may be accurately advised as to the position of the said table. The signal lamps 70 are provided with white lenses 71 which show white lights in the directions of the ends of the rails 12 so as to indicate to the engineers 85 of approaching trains that the table is properly positioned. Assuming that the table is in the position indicated in Fig. 1, the white lights will be facing the rail sections 36 and a red lens 62 also carried by each 90 signal lamp 70, will face the rail sections 34 so as to advise the engineers of trains approaching in this direction that the table is improperly positioned or not alined with the sections 34. As illustrated in Figs. 5 and 6, 95 each signal lamp 70 is supported by an L-shaped standard 64 having an attaching portion 65 which is adapted to be connected with brackets or sleeves 66 secured by any suitable means to the base. The L-shaped 100 formation of the standards 64 spaces the lamps 70 a considerable distance from the rail sections 12 so that trains may readily pass over the table and will not strike the lamps. 105

With reference to the foregoing description, taken in connection with the accompanying drawings, it will be noted that a railroad crossing constructed in accordance with this invention may be readily positioned for allowing of the passage of a train from either direction and by reason of the fact that the ends of the rails 12 are positioned close to the ends of the rails 34 and 36, the bumping caused by the passage of rolling stock over the joints of the rails in an ordinary crossing is eliminated. 115

It is to be understood that the form of the invention herewith shown and described is to be taken as a preferred example of the 120 same and that such minor changes in arrangement and construction of parts may be made as will remain within the spirit of the invention and the scope of what is claimed.

Having thus described the invention, 125 what is claimed as new is:

1. A rail crossing comprising a base having an upstanding annular side wall, a table mounted upon said base, said upstanding side wall of the base and the adjacent por- 130

tion of said table being formed with a race-way, anti-friction devices arranged in said raceway, and rail sections mounted upon said table.

5 2. A rail crossing comprising a base having an upstanding annular side wall, a table mounted upon said base, said upstanding side wall of the base and the adjacent portion of said table being formed with a race-way, anti-friction devices arranged in said raceway, rail sections mounted upon said table, and a flange carried by said table and surrounding the adjacent portion of said side wall.

15 3. A rail crossing comprising a base having an upstanding side wall, a table mounted upon said base and extending over said upstanding side wall, said table being provided with a centrally arranged journal 20 rotatably connected to said base, anti-friction devices arranged between the upstanding side wall of said base and the extended portion of said table, rail sections connected to said base, and rail sections mounted upon 25 said table.

4. A rail crossing comprising a base, a table rotatably mounted upon said base, rail sections mounted upon said table, upstanding brackets formed integral with the base, and rails connected to said brackets. 30

5. A rail crossing comprising a base, a table rotatably mounted upon said base, rail sections mounted upon said table, upstanding brackets formed integral with the base, rails connected to said brackets, and an operating device for said table. 35

6. A rail crossing having a base comprising an upstanding side wall, a table mounted upon said base and extending over said upstanding side wall, said table being 40 provided with a journal rotatably connected to said base, anti-friction devices arranged between the upstanding side wall of said base and the extended portion of said table, rows of upstanding lugs mounted on 45 said table, and rail sections confined between said lugs.

In testimony whereof I affix my signature.

WILLIAM G. STOCKHAM. [L. S.]
